UNITED STATES PATENT OFFICE.

AMOS W. WARNOCK, OF BOSTON, MASSACHUSETTS.

PIPE-CUTTER.

SPECIFICATION forming part of Letters Patent No. 729,816, dated June 2, 1903.

Application filed November 6, 1902. Serial No. 130,246. (No model.)

To all whom it may concern:

Be it known that I, AMOS W. WARNOCK, a citizen of the United States, residing in Boston, in the county of Suffolk and State of Massachusetts, have invented new and useful Improvements in Pipe-Cutters, of which the following is a specification.

This invention relates to tools for cutting metallic pipe, said pipe being held immovable in a vise or similar machine or instrument, the pipe being cut by swinging, preferably in an upward direction, the handle of the pipe-cutter.

The invention consists in a certain novel construction and arrangement of parts whereby the pipe is cut with greater ease and certainty, the movable jaw adjusted quickly, and the operation of the implement improved and rendered quicker.

The nature of the invention is fully described below and illustrated in the accompanying drawings, in which—

Figure 1 is a side elevation of a pipe-cutter embodying my invention, showing a piece of pipe in section in position, a portion of the rod being broken out. Fig. 2 is a plan view of the same. Fig. 3 is a view of the under side, a portion of the rod being broken off. Fig. 4 is a longitudinal section taken on line 30 4, Fig. 2. Fig. 5 is a transverse section taken on line 5, Fig. 4. Fig. 6 represents a cutting-knife provided with four cutting edges. Fig. 7 is a view of a cutter provided with a single cutting edge.

Similar letters of reference indicate corresponding parts.

a represents the parallel sides, and *a' a''*, respectively, the front and rear ends of a rectangular open metallic frame. The ends *a' a''* are bored to receive the smooth portions of a round rod or handle-bar *b*, which is screw-threaded between said ends within the frame. The handle-bar is held in position on one side of the end *a'* by a nut *c* and on the other side by a suitable shoulder formed by having the bar where it passes through the end *a'* of smaller diameter than the main threaded portion, as shown in Fig. 4. The outer end of the handle-bar is provided with the round disk-shaped rigid handle *e*, formed on its periphery with depressions or concave notches *e'* for the purpose of aiding the hand in ob-

taining a better grip. In using this instrument the handle is swung up, and in my device it is made round and substantially flat 55 instead of T-shaped, as is commonly the case, in order that as it is swung up its shape will accommodate or facilitate the natural turn of the wrist.

Extending rearward from the frame and integral therewith is the tubular guide *g*, from which there extends the parallel ears *h*, said ears operating as a stationary jaw and supporting, by means of a suitable screw *d* in either of the holes *f*, a cutting-knife *k*, below 65 described.

p represents a movable jaw provided with the angle-shaped or other suitably-formed surface *p''* for engaging with a pipe *s*, with the flanges *p'*, which are seated on the upper side 75 of the frame, and with the extension *m*, which is horizontally bored at *m'* and extends down through the frame and beneath it bends rearward at *n* and is provided on opposite sides of its end with rollers *o*. The upper 75 side of the bore *m'* is threaded to correspond with the screw-thread on the rod *b*, while the under side is smooth, said bore being made somewhat larger in diameter than the threaded portion of the rod *b*. The rollers *o* are of 80 suitable diameter to bear against the under edge of the frame when the movable jaw is seated on the upper edge thereof.

The cutting-knife *k* is provided at its operative end with a notch *u*, termed a "clearance," a blunt edge *v*, preferably slightly rounded and at a suitable angle to bear centrally against the pipe above the center thereof, and a cutting edge *w*, which is at an obtuse angle with the lower edge of the cutter 90 and projects upward into a cutting-point *w'*, which is at an acute angle with the clearance *u*. This cutter may have two opposite operative cutting edges or operative portions, as in Figs. 1 and 4, or one, as shown in Fig. 7, or 95 four radially arranged, as shown in Fig. 6.

In operation the pipe is placed between the cutting-knife and the jaw *p* and said jaw rocked or swung toward the cutter, such rocking being rendered possible by the size of the bore *m'* and the smoothness of its bottom, and the jaw moved against the pipe, such movement being facilitated by the rollers *o*. The pipe is then forced snugly against the

cutting-knife *s* by rotating the rod *b* by means of its handle *e*, which by means of its thread carries the movable jaw *p* toward the knife. The knife then assumes the position shown 5 in Fig. 1, such position being forced by the shape of the pipe, the dead-rest *v* bearing against the pipe above its center and the point *w'* of the knife bearing against the pipe below its center. The pipe being held 10 movably in a vise, the handle *e* is swung up, with the effect that while the dead-rest slips over the pipe and holds the cutter in position the cutting edge *w w'* of the knife cuts the pipe, the notch *u* acting as a clearance. 15 It should be understood that as the knife is held pivotally on the pin or screw *d* it is forced by the pipe itself into the position illustrated—*i. e.*, with the dead-rest bearing above the center and the cutting edge below 20 the center—so that the knife-point cuts up toward the center and is constantly held in the same relative position by the rest, which bears on the pipe.

Having thus fully described my invention, 25 what I claim, and desire to secure by Letters Patent, is—

1. In a pipe-cutter, a slotted or open frame; a movable jaw adapted to slide on said frame; an extension projecting downward through 30 said slot and rearward beneath the frame and adapted to bear against the under side of the frame when the pipe is held in position; a rod in engagement with the movable jaw and adapted to be disengaged and allow the jaw 35 to rock when it is not engaging with a pipe; a stationary jaw rigidly connected with the frame; and a cutting-knife supported by the stationary jaw, substantially as described.
2. In a pipe-cutter, a slotted or open frame; 40 the movable jaw *p* provided with the hori-

zontally-bored downward projection *m* extending forward beneath and bearing against the under side of the frame when the jaw is engaging the pipe; a stationary jaw extending rigidly from the frame; and a rod extending through and having bearings in the frame and the bore on said extension, and with its portion inside the frame screw-threaded, said bore being somewhat larger in diameter than the threaded portion of the 50 rod and being provided on its upper side with a screw-thread, whereby the stationary jaw is held rigidly in position when it is in operation but is free to be rocked out of engagement with the thread on the rod when the 55 pipe is released, substantially as set forth.

3. In a pipe-cutter, the longitudinally-slotted or open frame *a, a', a''*; the movable jaw *p* seated on said frame by means of the flanges *p'*; the extension *m* horizontally bored at *m'*, 60 extending down through the frame, and bent rearward at *n*; suitable rollers supported by the portion *n* and bearing against the under side of the frame; the rigid jaw *h* extending from the frame; the rod *b* extending through 65 said bore and having bearings in the frame, said rod being adapted to engage with the movable jaw when said movable jaw is in engagement with the pipe; and the disk-shaped handle *e* on the outer end of the rod, said 70 handle being provided with the peripheral notches *e'*, substantially as described.

In testimony whereof I have signed my name to this specification in the presence of two subscribing witnesses.

AMOS W. WARNOCK.
